US0D1026670S

(12) **United States Design Patent** (10) **Patent No.:** **US D1,026,670 S**
(45) **Date of Patent:** **** May 14, 2024**

(54) **SHAPED CONTAINER**

- (71) Applicant: **Silgan Containers LLC**, Woodland Hills, CA (US)
- (72) Inventors: **Andrew Palumbo**, Conshohocken, PA (US); **Thomas J. Snyder**, Westlake Village, CA (US); **Alvin Widitora**, Los Angeles, CA (US)
- (73) Assignee: **Silgan Containers LLC**, Woodland Hills, CA (US)
- (**) Term: **15 Years**
- (21) Appl. No.: **29/873,665**
- (22) Filed: **Apr. 5, 2023**

Related U.S. Application Data

- (62) Division of application No. 29/786,792, filed on Jun. 2, 2021, now Pat. No. Des. 986,067, which is a division of application No. 29/686,646, filed on Apr. 5, 2019, now Pat. No. Des. 924,075.
